UNITED STATES PATENT OFFICE.

GEORGE A. YANOCHEWSKI, OF CHICAGO, ILLINOIS, AND HARRY E. HERSHY, OF WHITEWATER, KANSAS, ASSIGNEES TO AUTOMATIC ELECTRIC COMPANY, OF CHICAGO, ILLINOIS, A CORPORATION OF ILLINOIS.

SEMI-AUTOMATIC TELEPHONE SYSTEM.

1,353,300.

Specification of Letters Patent Patented Sept. 21, 1920.

Original application filed November 25, 1914, Serial No. 874,054. Patent No. 1,317,190. Divided and this application filed July 25, 1917, Serial No. 182,663. Renewed January 28, 1920. Serial No. 355,584.

To all whom it may concern:

Be it known that we, GEORGE A. YANOCHEWSKI and HARRY E. HERSHY, both citizens of the United States of America, and residents of Chicago, Cook county, Illinois, and Whitewater, Butler county, Kansas, respectively, have invented certain new and useful Improvements in Semi-Automatic Telephone Systems, of which the following is a specification.

Our invention relates to telephone systems and is particularly applicable to manual telephone systems. Among the objects of our invention are the following:

To provide means whereby when a subscriber removes his receiver he immediately supplies a guarding potential to the multiple jacks of his line; to provide means for automatically giving a calling subscriber a signal as soon as the operator disconnects from his line to indicate to him that he should hang up his receiver; to provide means whereby a B operator can automatically give an A operator a disconnect signal by merely dropping the calling plug; to provide means for automatically giving one operator a disconnect signal from another operator's position by automatically varying the resistance of the talking circuit between the two cords; and to provide other details and features of improvement and combination tending to increase the efficiency and serviceability of a telephone system. Means for accomplishing the foregoing and other useful ends are hereinafter set forth and claimed.

This application is a division of our application Serial No. 874,054, filed November 25, 1914, Patent No. 1,317,190, issued Sept. 30, 1919. The features of our invention that we desire to patent in this division are those capable of separate and independent use either with single exchange apparatus or with different types of divided exchange apparatus.

In the accompanying drawings Figures 1 and 2 show a complete connection in a manual telephone system embodying the principles of our invention.

Fig. 1 shows the manual substation T, an answering jack equipment J, multiple jacks M and an A operator's cord circuit S.

Fig. 2 shows a manual substation T', an answering jack equipment J', multiple jacks M and a B operator's cord circuit I. 55

The manual substation T is an ordinary common battery manual telephone comprising the usual receiver 2, transmitter 3, ringer 4 and condenser 5. The substation T' is similar to the substation T. 60

The answering jack equipment J consists of the usual line relay 6, cut-off relay 7, line lamps 8 and an answering jack 9. And in addition there is provided the slow acting relay 10. The answering jack equipment J' is similar to that shown at J except that the relays 6 and 10 are replaced by the one double wound relay 11^a. The relay 11^a is so constructed and adjusted that when a circuit is closed through its left hand winding 70 and not through its right hand winding the armature 93 alone will be attracted.

The A operator's cord circuit S is a well known type of cord circuit comprising the usual answering and calling plugs P and P', respectively, inductively connected together through the medium of a repeating coil R. The usual supervisory relays 11 and 12 are included in the sides of the cord circuit for controlling the supervisory lamps 80 13 and 14.

The B operator's cord circuit I comprises the plug P², the supervisory lamp 15 and relays for controlling the same. At 16 is shown a plug seat switch whose springs are 85 separated when the plug P² is in its seat.

For the purpose of supplying battery current for operating the apparatus and for talking purposes, there is shown the battery B, having one terminal grounded at G. 90 The busy signaling machines Q' and Q², as represented herein, comprise an induction coil or transformer, the primary winding of which is included in a local circuit with a battery and an interrupter. Through the 95 medium of this interrupter an interrupted current is supplied to the primary winding, which induces an alternating current in the secondary winding, whereby when said winding is connected with the subscriber's line, a buzzing sound is heard in the receiver.

A general description of the apparatus having been given, it will now be explained

how connection can be established between the line of substation T and the line of called substation T'.

Upon the removal of the receiver at the

- 5 calling substation a circuit may be traced from ground G' through springs 17 and 18, to and through substation T, springs 19 and 20 and the relay 6 to battery B. The relay 6, upon energizing, places ground from G²
 10 upon the bush of all the multiple jacks associated with the line of substation T, and in addition closes a circuit from ground G³, through springs 21 and 22, lamp 8, springs 23 and 24 to battery B.
 15 The operator upon seeing the lamp 8 glowing, knows that a connection is desired and thereupon inserts the plug P into the jack 9. A circuit may now be traced from ground G⁴ through relay 25, sleeve of plug
 20 P and bush of jack 9, relay 7, relay 10 to battery B. The relays 25, 7 and 10 energize over the above circuit, the relay 7, upon energizing, removes the line relay 6 from the line and extends the connection to the
 25 cord circuit S. The relay 10, upon energizing, removes ground G³ from the circuit of lamp 8. The relay 25, upon energizing, closes the circuit of lamp 13 at the springs 25^a, but this is without effect as the said circuit is opened at the springs 27, as will be hereinafter explained. Upon the energization of relay 7 a circuit may be traced from ground G⁵ through winding 28 of repeating coil R, tip of plug P and of jack 9, springs
 30 19, to and through substation T, springs 18 and 18^a, ring of jack 9 and of plug P, relay 11, winding 29 of repeating coil R to battery B. The relay 11, upon energizing, opens the circuit of the lamp 13 at the springs 27.
 35 The A-operator now depresses the key K, thereby cutting her talking set across the calling line, and converses with the calling subscriber. Upon learning the number of the called subscriber the A-operator depresses the order wire key K', and repeats the number to the B-operator, the B-operator then assigns the trunk to be used.

- The B-operator upon receiving an order, raises the plug P², associated with the trunk she has assigned to the A-operator, from its plug switch seat 16 and touches the bush of the jack of the called line with the tip of the said plug. If the line is idle, the B-operator then inserts the plug P² into the jack M and in so doing closes a circuit from ground G⁶ through relay 30, sleeve of plug P² and bush of jack M, springs 31, the two windings of relay 11^a in series to battery B. The relay 11^a, upon energizing, removes the line relay 32 from the called line. The relay 30, upon energizing completes the talking circuit through the cord circuit I. Upon the removal of the plug P² from the plug seat switch 16, a circuit may be traced from ground G¹⁶ through springs 16, relay 35 to

battery B. The relay 35, upon energizing, closes a circuit through the lamp 15 which is without effect at this time, since the said lamp will immediately be extinguished as hereinafter explained.

The A-operator, upon being assigned a trunk, inserts the plug P' into the jack 33, associated with the assigned trunk. A circuit may now be traced from ground G⁷ through resistance 36, bush of jack 33 and 70 sleeve of plug P', relay 37 to battery B. The relay 37, upon energizing, closes a circuit from ground G⁸ through springs 38, lamp 14, springs 39 to battery B. The glowing of lamp 14 informs the A-operator that the 75 called party has not answered. As a further result of the insertion of the plug P' into the jack 33, another circuit may be traced from ground G⁹ through winding 34 of repeating coil R, tip of plug P' and of jack 80 33 conductor 90, resistance 40, relay 41, conductor 91, ring of jack 33 and of plug P', relay 12, winding 42 of repeating coil R to battery B. The resistance 40 is high enough that relay 12 will not operatively energize 90 over the above circuit, the relay 41, however, energizes and opens the circuit of the lamp 15 at the springs 43.

Returning to the operation of the B-operator's cord circuit Fig. 2 it will be seen 95 that upon the energization of the relay 30 a circuit is closed from ground G⁹ through interrupter 44, springs 45, springs 46, and ringer relay 47 to battery B. The ringer relay 47 energizes intermittently due to the 100 interrupter 44 and operates to disconnect the called line from the cord circuit and bridge the ringing current generator R in series with battery B across the called line. The circuit may be traced from ground G¹⁰ 105 through springs 48 and 48^a, springs 49 and 50, tip of plug P² and of jack M, springs 51 and 52, through ringer and condenser at substation T', springs 53 and 54, ring of jack M and of plug P², springs 55 and 56, 110 upper winding of relay 57, generator R, and through battery B to ground G. The ringer at substation T' will be energized by the ringing current, but the relay 57 is so adjusted that it will not respond to the said 115 ringing current. Upon the response of the called subscriber a path for direct current will be formed at the substation T' whereupon the relay 57 will become energized. The relay 57, upon energizing, opens the circuit of the ringer relay at the springs 45, in addition forms a locking circuit for itself from ground G¹¹ through the lower winding of relay 57, springs 58, springs 59 to battery B. Upon the deenergization of ringer relay 120 47 battery and ground are supplied to the called line through the relay 60 and 61. The relay 60, upon energizing, shunts the resistance 40 at the springs 62, this increases the flow of current in the trunk to such an ex- 130

tent that the relay 12 becomes energized and opens the circuit of the lamp 14. The extinguishing of the lamp 14 notifies the A-operator that the called subscriber has answered.

Upon the completion of the conversation the restoring of the receiver at the calling substation opens the circuit of the relay 11. The relay 11, upon deenergizing, closes a circuit from ground G^{12} through springs 27, springs 25^a and lamp 13 to battery B, thus causing said lamp 13 to glow. The restoring of the receiver at the called substation opens the circuit of the relay 60, which, upon deenergization, removes the shunt from around the resistance 40. This added resistance in the trunk causes the relay 12 to release its armature thus again closing the circuit of the lamp 14. The A-operator, upon seeing both the lamp 13 and the lamp 14 lighted knows that a disconnect is desired and forthwith removes the plugs P and P' from their respective jacks. The removal of the plug P' from the jack 33 opens the circuit of relay 41, which, upon deenergizing, closes a circuit from ground G^{13} through springs 43, lamp 15, springs 59 to battery B. The glowing of the lamp 15 informs the B-operator that the A-operator has taken down the connection, whereupon the B operator removes the plug P² from the jack M. The restoring of the plug P² to the plug seat switch 16 opens the circuit of the relay 35. The relay 35 upon deenergizing opens the circuit to the lower winding of relay 57.

It having been explained how a connection can be established between a calling and a called subscriber and how the same is released, it will now be explained how a connection is prevented from being made with a busy line and how the connection is then taken down and the calling subscriber given the busy signal from his answering jack equipment. If the called line should be busy, there will be a ground potential upon the bush of all the multiple jacks associated with that line. When the B-operator touches the tip of the plug P² to the bush of a busy multiple jack, a circuit will be formed from ground potential at the multiple jack through tip of plug P², springs 50 and 63 and tertiary winding 64 of induction coil to battery B. This flow of current will cause a click in the B-operator's receiver which will inform her that the called number is busy, whereupon she returns the plug P² to its plug seat switch 16, thus opening the circuit of the relay 35. The relay 35, upon deenergizing, closes a circuit from ground G^{14} through interrupter 65, springs 66, springs 67, relay 68 to battery B. The relay 68 energizes intermittently, due to the interrupter 65 and operates to periodically shunt the resistance 40 at the springs 69.

The shunting of the resistance 40 causes the lamp 14 to be intermittently extinguished thus informing the A-operator that the called number is busy. The A-operator then removes the plugs P and P' from their respective jacks. The removal of the plug P from the jack 9 opens the circuit of the cut-off relay 7, which, upon deenergizing, closes a circuit from ground G' , through springs 17 and 18, to and through substation T, springs 19 and 20 and relay 6 to battery B. The relay 6, upon energizing, closes a circuit from ground G^2 through springs 70 and 71, springs 72, relay 10 to battery B. The relay 10, being slow acting, did not deenergize immediately upon the withdrawal of the plug P, but remained energized long enough for the above traced circuit to be formed, after which it of course locks-up. Another circuit is now formed from ground G^{15} through interrupter 73, secondary of busy machine Q', springs 74, springs 75 to and through the substation T, springs 18 and 17 to ground G' . The calling subscriber upon hearing the busy tone will know that the called number is busy and will then return his receiver to the receiver hook, thereby causing the deenergization of line relay 6, which in turn allows the relay 10 to deenergize. It will be seen that as long as the calling subscriber is receiving the busy tone there will be a guarding potential from ground G^2 upon all of the multiple jacks associated with that line.

It will be seen therefore that we have provided an improved arrangement whereby as soon as a subscriber's line relay energizes a guarding potential is applied to the multiple jacks M so as to make the calling line busy even before the operator answers. We have also provided an improved arrangement whereby the line relay of the subscriber controls the signal for the operator and also controls a signal for the subscriber to indicate to him that he should hang up his receiver and call again. We also provide means whereby the B operator through the medium of a plug seat comprising the plug 16 is enabled to give the A operator automatically a busy flash signal by varying the resistance on the line between the two cords. The means for accomplishing this comprises, of course, the relay 68 and the interrupting machine 65.

Therefore it will be seen that we have provided an improved system in which the efficiency of the equipment is increased by simplifying the matter of signaling.

What we claim as our invention is:

1. In a telephone system, a line, a line relay, a cut-off relay, an auxiliary relay, a trunk, a locking circuit for said auxiliary relay, means for energizing said auxiliary relay and said cut-off relay comprising a battery, a source of signaling current com-

mon to said system, a signaling circuit individual to said line, manual means for connecting said trunk and line, means for closing said battery circuit to energize said 5 cut-off relay and said auxiliary relay when the said connection is made, the said auxiliary relay operating when energized to connect the said source of signaling current with said individual circuit, an energizing 10 circuit for said line relay controlled by said cut-off relay, and means for breaking the energizing circuit of the said auxiliary relay and of the cut-off relay when the line and trunk are disconnected, the cut-off relay 15 operating upon deenergizing to close the circuit of the line relay for energizing the same to connect the said signaling current via said individual signaling circuit with said line for signaling the line, said line relay 20 operating also to close the locking circuit of said auxiliary relay before the auxiliary relay has time to deenergize.

2. In a telephone system, a subscriber's line, a cord circuit connected with said line, 25 a busy signaling device and means for automatically sending a busy signal over the line when the cord is withdrawn from the line until cut off by the subscriber, and automatic means responsive to the cutting off 30 by the subscriber to remove the signal from the control of the subscriber.

3. In a telephone system, a subscriber's line, a cord circuit connected with said line, a busy signaling device and means individual 35 to the line for automatically sending a busy signal over the line when the cord is withdrawn from the line until cut off by the subscriber, and automatic means responsive to the cutting off by the subscriber 40 to remove the signal from the subscriber's control.

4. In a telephone system, a manual subscriber's line and a trunk connected in circuit, means for separating the two, and 45 means responsive when the connection is broken for applying a signal to the line until cut off by the subscriber, and automatic means responsive to the cutting off by the subscriber to remove the signal from the subscriber's control.

5. In a telephone system, a subscriber's line and a trunk connected in circuit, manual means for separating the two, and automatic means responsive when the connection 55 is broken for applying a signal to the line until cut off by the subscriber, and automatic means responsive to the cutting off by the subscriber to remove the signal from the subscriber's control.

60 6. In a telephone system, a subscriber's line and a cord connected in circuit, a line relay, means for separating the cord and circuit, and means comprising said relay responsive when the connection is broken for 65 applying a signal to the line until cut off by

the subscriber, and automatic means responsive to the cutting off by the subscriber to remove the signal from the subscriber's control.

7. In a telephone system, a subscriber's line and a cord connected in circuit, a line relay, manual means for separating the cord and circuit, and automatic means comprising said relay responsive when the connection is broken for applying a signal to the line until cut off by the subscriber, and automatic means responsive to the cutting off by the subscriber to remove the signal from the subscriber's control.

8. In a telephone system, a line, a trunk, 80 a line relay, an auxiliary relay, a source of signaling current common to said system, a signaling circuit individual to said line, means for connecting said trunk and line, said auxiliary relay responsive when the 85 connection is made for connecting said source of signaling current with said individual signaling circuit, said line relay responsive when the connection is broken for connecting said signaling current via said 90 individual signaling circuit with said line for signaling the line.

9. In a telephone system, a line, a trunk, a line relay, an auxiliary relay, a source of signaling current common to said system, a 95 signaling circuit individual to said line, manual means for connecting said trunk and line, said auxiliary relay responsive when the connection is made for connecting said source of signaling current with said individual signaling circuit, said line relay responsive when the connection is broken for automatically connecting said signaling current via said individual signaling circuit 100 with said line for signaling the line.

10. In a telephone system, a line, a trunk, a line relay, a slow acting auxiliary relay, a source of signaling current common to said system, a signaling circuit individual to said line, manual means for connecting said 110 trunk and line, said auxiliary relay responsive when the connection is made for connecting said source of signaling current with said individual signaling circuit, said line relay responsive when the connection 115 is broken for automatically connecting said signaling current via said individual signaling circuit with said line for signaling the line.

11. In a telephone system, a line, a trunk, 120 a line relay, an auxiliary relay, a source of signaling current common to said system, a signaling circuit individual to said line, means for connecting said trunk and line, said auxiliary relay responsive when the 125 connection is made for connecting said source of signaling current with said individual signaling circuit, said line relay responsive when the connection is broken for connecting said signaling current via said 130

- individual signaling circuit with said line for signaling the line, and a locking circuit for said auxiliary relay controlled by said line relay.
- 5 12. In a telephone system, a line, a trunk, a line relay, an auxiliary relay, a source of signaling current common to said system, a signaling circuit individual to said line, manual means for connecting said trunk and line, said auxiliary relay responsive when the connection is made for connecting said source of signaling current with said individual signaling circuit, said line relay responsive when the connection is broken for automatically connecting said signaling current via said individual signaling circuit with said line for signaling the line, and a locking circuit for said auxiliary relay controlled by said line relay.
- 10 13. In a telephone system, a line, a trunk, a line relay, a slow acting auxiliary relay, a source of signaling current common to said system, a signaling circuit individual to said line, manual means for connecting said trunk and line, said auxiliary relay responsive when the connection is made for connecting said source of signaling current with said individual signaling circuit, said line relay responsive when the connection is broken for automatically connecting said signaling current via said individual signaling circuit with said line for signaling the line, and a locking circuit for said auxiliary relay controlled by said line relay.
- 15 14. In a telephone system, a line, a line relay, a cut-off relay, an auxiliary relay, a trunk, a locking circuit for said auxiliary relay, means for energizing said auxiliary relay and said cut-off relay comprising a battery, a source of signaling current common to said system, a signaling circuit individual to said line, means for connecting said trunk and line, means for closing said battery circuit to energize said cut off relay and said auxiliary relay when the said connection is made, the said auxiliary relay operating when energized to connect the said

source of signaling current with said individual signaling circuit, an energizing circuit for said line relay controlled by said cut-off relay, and means for breaking the energizing circuit of the said auxiliary relay and of the cut-off relay when said line and trunk are disconnected, the cut off relay operating upon deenergizing to close the circuit of the line relay for energizing the same to connect the said signaling current via said individual signaling circuit with said line for signaling the line, said line relay operating also to close the locking circuit of said auxiliary relay before the auxiliary relay has time to deenergize.

15. In a telephone system, a subscriber's line, a line relay, a signal for said line, means comprising said relay operable over said line for bringing said signal into operation, a cord, means controlled from said cord for retiring said signal, another signal, means comprising said relay controlled from said cord for applying said last signal to said line, and means for preventing the subscriber from applying said second signal to the line.

16. In a telephone system, a subscriber's line, a jack for said line normally disconnected therefrom, a cut-off relay for said line, a cord, a plug and an energizing circuit for said cut-off relay, means for closing said circuit when said plug is inserted in said jack and for energizing said cut-off relay, and means controlled by the energization of said relay for connecting said line and said jack to extend a connection from the line to the cord, and means controlled by said cut-off relay for applying a signal to said line, and for preventing the subscriber from applying said signal to his line.

Signed by me at Chicago, Cook county, Illinois, this 12th day of July, 1917.

GEORGE A. YANOCHOWSKI.

Signed by me at St. Paul, Ramsey county, Minnesota, this 16th day of July, 1917.

HARRY E. HERSEY.
